[57] CLAIM

The ornamental design for a swivel rack, as shown and
described.

DESCRIPTION

FIG. 1 is a front elevational view of a swivel rack showing
our new design; the rear being a mirror image;
FIG. 2 is a side elevational view with the supporting
arms in an alternate position, the side opposite being a
mirror image;

FIG. 3 is a top plan view of FIG. 2;
FIG. 4 is a bottom plan view of FIG. 2; and,
FIG. 5 is a perspective view of FIG. 2.
